BOX SYSTEM

Ludwig H. Lange, Philadelphia, Pa., assignor to
 Stokes and Smith Company, Philadelphia, Pa.,
 a corporation of Pennsylvania

Application July 7, 1937, Serial No. 152,354

55 Claims. (Cl. 93—54.2)

My invention relates to box-forming or box-wrapping systems for applying sheet material as wrappers, labels, or the like, to box structures to form boxes, box covers, containers, or the like.

- 6   In accordance with one aspect of my invention, a box structure, such as a stayed or unstayed box, is transferred from a registering or aligning station into the path of the form block of a box machine by two transfer structures which successively engage the box structure; specifically, one of the transfer structures is a carriage which reciprocates between a box-receiving position and a discharge position in the path of the form block and the other transfer structure is a member which pushes the box structure from the aligning or registering station into the carriage; with reduction of output of the machine, the latter transfer device may be omitted and the box structure fed by hand to the carriage.
- 10   Further in accordance with my invention, each box structure is aligned or registered with the form block by mechanism timed to effect the aligning or registering operation before movement of the box structures by the transfer device.
- 15   More particularly and preferably, the box structures are transported to the aligning or registering station by a conveyor movable, in each cycle of the machine, while the transfer and aligning devices are out of the path of box structures on the conveyor.
- 20   My invention further resides in the features of construction, combination and arrangements hereinafter described and claimed.

For an understanding of my invention and for illustration of a preferred form thereof, reference is to be had to the accompanying drawings in which:

- Figure 1 is a front elevational view of a box machine and feeding means therefor;
  - 40   Fig. 2 is an end elevational view, on enlarged scale, showing parts appearing in Fig. 1;
  - 45   Fig. 3 is a detail view showing one of the feeding or transfer devices in position different from that of Fig. 2;
  - 50   Fig. 4 is a detail view showing another transfer device of Fig. 2 in different operating position;
  - 55   Figs. 5 and 6 are sectional plan views of valve mechanism shown in Fig. 2;
  - 55   Figs. 7 to 10, in perspective, show the transfer devices of Fig. 2 in various operating positions;
  - 55   Fig. 11 illustrates a modification.
- Referring to Fig. 1 the box machine M is generally of the type shown in Smith U. S. Patent #691,329, and more specifically of the type shown in Rider et al. U. S. Patent #2,074,561. The main

cam 1 attached to shaft 2 is driven from a motor, not shown, through the clutch comprising the driving element 3 and the driven element 4. The operator, to initiate operation of the machine, depresses the pedal 5 causing the arm 6 to withdraw a pin 7 from engagement with the adjustable cam 8 rotatable with shaft 2; a spring, not shown, is thereupon effective to move the driven clutch element 4 into driving engagement with the driven clutch member 3; at the end of one revolution of shaft 2 the cam 8 through pin 7 rocks the bell-crank lever 9 in clockwise direction to withdraw the driven clutch member 4 and so interrupt operation of the machine, provided the operator does not hold the pedal 5 depressed in which event the cycle repeats.

During a revolution of the cam 1, the form block F, comprising the upper form UF and the lower form LF is moved from the position shown in Fig. 1 downwardly in a path adjacent various sheet-applying tools and thence back to its original position shown in Fig. 1. This movement of the form block and relative movements with respect to each other of the form-block components UF and LF are effected by the levers 10 and 11 provided, respectively, with cam followers 12 and 13 which ride in the cam grooves 14 and 15 of cam 1. As well understood in the art, the size of the form block is selected to suit the particular boxes to be made or wrapped by the machine.

The various sheet-applying tools, including the side rolls 16, end rolls not shown, marginal turn-in tools 17 and presser blocks 18 are carried by four tool slides 19 adjustably secured to the table 20 of the machine and each provided with an operating member 21 adjustably secured to a bar 22 extending from a slidable sleeve 23 connected by link 24 to a lever 25 carrying a cam follower 26 received by groove 27 of cam 28 disposed on the one-time shaft 2 of the machine. During each cycle of the machine, the sleeve 23 is reciprocated to effect the various sheet-applying operations of the tools, all as more fully shown and described in the aforesaid Rider patent.

The conveyor C is intermittently operated, making one step for each cycle of the box machine M, to transport adjacent to the form-block structure F box structures, wrappers, groups of tabs, or specifically assemblies, such as shown for example in Stokes U. S. Patent #2,015,202, each comprising an unstayed box or component of a multi-piece box to which is attached partially applied sheet material. The sheet material partially applied to an unstayed box may simply be tabs, or a wrapper having tabs thereon, or an

untabbed wrapper. Alternatively, each of the assemblies may comprise a previously stayed box and a partially applied tabbed or untabbed wrapper. Conveyor C, preferably of the suction type as in Davis U. S. Patent #1,818,198, may transport the wrappers from a gluing machine, such as shown in Rider U. S. Patent #1,857,260 or Federwitz U. S. Patent #1,772,344, and at an intermediate point between the gluing machine and the wrapping machine an operator may manually register boxes on the wrappers to form the assemblies, or this operation of forming assemblies may be performed automatically, as by mechanism disclosed in Stokes Patent #2,018,237.

18 For purposes of explaining the operation of the machine, the assemblies operated upon each comprises a one-piece unstayed box B, and a one-piece wrapper W to which tabs t are previously applied as by mechanism of the aforesaid Rider patent. The conveyor C is preferably of the suction type so that the wrappers are held flat by suction at least until they pass the assembly station at a suitable point along the suction housing H.

25 As each assembly A in turn arrives in position adjacent the form block, the leading edge or end of the box structure B is engaged by an adjustable stop member 29 extending transversely of the conveyor belt C and held in position slightly above it by the bolt 30a, Fig. 2, which clamps stop 29 to the plate 101 for supporting conveyor belt C. The spacing of the stop 29 above the conveyor permits the leading end of the wrapper to pass below it without obstruction, yet per-

30 mits the stop 29 to engage the forward end of the stayed or unstayed box. The stop 29, as appears in Fig. 7, is in alignment or registry with one end of the form-block structure F. This element of itself is not sufficient to provide for alignment of the box or unstayed box with the form block because of the tendency of the box structure to rebound from the stop; further, when the box structure is an unstayed blank, the end wall is not erected and therefore, although the forward edge of the blank might remain against the stop 29 upon termination of the conveyor movement, the blank, if moved transversely of the conveyor into the path of the form block, would not be in alignment or registry with the form block.

50 To insure proper alignment of the box structure with the form block, and additionally in the case of the unstayed blank to erect the end walls of the blank, there is provided an aligning or registering mechanism R comprising the arm 32, Fig. 2, attached to shaft 33 and having at its free end a box-engaging member 33a which, when the arm 32 is in its lower position, Fig. 8, preferably just clears the top of the conveyor belt C and which, when in its upper position, Figs. 2 and 7, is out of the path of box structures on the conveyor to avoid obstruction to their movement toward the stop 29. When the member 33a is in its down position, Fig. 8, it is in alignment with one end of the form block F, and the stop 29, as previously stated, is in alignment with the opposite end of the form block. The swinging movement of the arm 32 is, therefore, effective, in the case of stayed boxes, to align them with the form block, and in case of unstayed boxes, performs the additional function of erecting the box ends so that they are in alignment with the ends of the form block structure F.

75 The aligned or registered box structure is

5 moved from the position shown in Fig. 8 toward the path of the form block F by transfer mechanism P including the arm 35 pivotally mounted at one end of the reciprocable carriage 36 and at its other end having a suction plate 37 for engagement with a box structure on the conveyor C. During movement of the conveyor C the arm 35 is in its upper position, Figs. 2 and 7, permitting the box structures to move with the conveyor without obstruction by arm 35 or the suction plate 37.

10 After the box structure has been aligned by the registering mechanism R, as above described, the arm 35 is rocked in clockwise direction to effect engagement of the suction plate 37 with the box blank, Fig. 8. This movement of the arm 35 is effected by the mechanism now described. Arm 35 is attached to shaft 38, Fig. 7, supported by the brackets 39 of carriage 36 and to shaft 38 is also attached the arm 40 upon the end of 20 which is mounted a roller 41 received by a groove or slot 42 in the member 43, Fig. 2, from which depend the supporting members 44, 45 pivotally mounted to the arms 46, 47 of bell-crank levers 48, 49 supported from the bracket 50 attached 25 to the main frame of the machine. The arms 51, 52 of the bell-crank levers 48, 49 are pivotally connected to the bar 53 which extends toward the rear of the machine and is there pivotally connected to the lower end of a lever 54, Fig. 10, 30 supported by, and free to rotate with respect to, the shaft 55. From lever 54 extends the arm 56 having thereon a cam follower 57 for engaging the cam 58 formed on the under side of the cam member 59, Fig. 2, which rotates with shaft 2. 35 Lever 54 is biased, as by a spring not shown, to maintain engagement of follower 57 with cam 58.

40 When the cam follower 57 moves upwardly under the control of cam 58, the lever 54 swings in clockwise direction to effect movement in the same direction of bell-crank levers 48, 49, thus lifting the grooved member 43 to swing the arm 35 in clockwise direction to effect engagement of the suction plate 37 with a registered box structure, Fig. 8. While the arm 35 remains in this angular position with respect to its shaft 38, the carriage 36 is moved toward the path of the form block to move the box structure to the position shown in Fig. 9. The mechanism for effecting this movement of the carriage is now described.

45 As shown in Figs. 2 and 7, the carriage 36 is supported by the two guide rods 60 whose ends are supported by the bracket 50. One end of the link 61 is connected at 62 to the carriage 36 and the other end of the link is connected, at the rear of the machine, to the lower end of a lever 63 attached to the shaft 55. The arm 64 of lever 63, Fig. 2, carries the cam follower 65 received by the groove 66 in the cam member 59 on shaft 2. 50

55 When, during the cycle of the machine, the lever 63 is swung in counterclockwise direction, the bar 61 is moved to the right, Fig. 2, to move the carriage 36 and the arm 35 thereon toward the path of the form block thus moving the box structure or assembly to the position shown in Fig. 9. After a predetermined dwell, the rise of cam 58 engages the cam follower 57 on lever 54 to move the link or bar 53 to the right, Fig. 2, to lower the member 43 and so cause the pusher-arm 35 to swing in counterclockwise direction to its upper position, shown in Fig. 2; concurrently the cam track 66 causes the arm 63 to swing in clockwise direction, moving the bar 61 to the left, and so returns the carriage 36 and arm 35 to its original position, shown in Fig. 7. 60

The arm 35 remains in its upper position until after the conveyor has moved another box blank into engagement with the stop 29, and the registering mechanism R has aligned it for transfer.

5 The movement of the arm 32 and box-engaging member 33a of the aligning mechanism R is derived from the member 43 whose reciprocation, as previously described, controls the movement of the pusher member 35. As shown in Figs. 2 10 and 8, to the front end of the shaft 33 which supports the arm 32 of the aligning member is attached the arm 68 connected by link 69 to a lever 70 pivoted on bracket 71 adjustably secured to bar 71a. The roller 72 on arm 70 is received by 15 a slot 73 in the extension 43a, Fig. 2, of the vertically reciprocating member 43.

When member 43 is lifted under the control of cam 58 to swing the arm 35 from the position shown in Fig. 7 to the box-engaging position 20 shown in Fig. 8, aligning arm 32 is therefore concurrently swung from the position shown in Fig. 7 to the position shown in Fig. 8 to register the stayed or unstayed box in anticipation of its movement towards the form block by the pusher-arm 35. During the forward movement of the pusher-arm, the aligning member 33a remains in its down position and serves as a guide for the box structure during its movement toward the position shown in Fig. 9.

25 30 When the member 43 is moved downwardly under the control of cam 58 to swing the arm 35 upwardly away from the conveyor, the operating arm 70 for the aligning member 33a is concurrently operated to swing the arm 32 from the 35 position shown in Fig. 9 to the position shown in Fig. 10, the arms 35 and 32 remaining in their upper positions until the member 43 is raised in the next cycle of the machine thus to avoid obstruction to movement of the box structures 40 toward stop 29.

To transfer the assembly A from the position shown in Fig. 10, into the path of the form block, Fig. 7, there are provided the members 74, 74 45 adjustably secured to the bars 75, 75 which, in turn, are adjustably secured to the movable supporting member 76 at the rear of the machine. The members 74, 74 of the second transfer device T extend from the rear of the machine, straddle the form block, and upon reciprocation of the 50 supporting member 76 move from the box-receiving position of Fig. 9, above the conveyor and displaced from the center thereof toward the form block, to the box-discharging position of Fig. 7. At their forward ends the members 74, 74 55 are provided with box-engaging or holding members 77, 77. The distance between members 77, 77 is adjustable to correspond to the length of the box structure to be transferred, the extreme outer ends of members 77 preferably being slightly 60 flared to facilitate entry of a box between the members. The inner faces of members 77, 77 are provided with ports 78 through which suction may be applied to hold the box against these members which serve as suction-type grippers. 65 For application of suction to the ports 78, the members 74, 74 are hollow and connect at their rear ends with the suction hose 79. Each of the members 77, 77 is provided with a stop 80 defining the limit of movement of the box structure by 70 the pusher-arm 35. From each of the members 74, 74 depends a supporting member 81 adapted, as most clearly shown in Fig. 2, to pass beneath and support the leading panel of a wrapper attached to the box structure to be transferred into 75 the path of the form block; members 81 may be

provided, as shown in Fig. 8, with suction ports 81a. The member 81 keeps the leading panel of the wrapper out of contact with parts of the mechanism, for example, the platen 82, during the transfer of the assembly to the position 5 shown in Fig. 7 above the platen which is biased to the position shown in Figs. 2 and 7, as by a spring not shown.

The carriage comprising the members 74, 74 is reciprocated between its box-receiving position 10 above the conveyor belt and its box-discharging position in the path of the form block F by the mechanism now described. The supporting structure 76 for members 74, 74 is connected by link 83 to the lower end of arm 84 pivoted at its 15 upper end to the bracket member 85 and connected by link 86 to arm 87 attached to the operating shaft 55 for the carriage 36 of the other transfer device 35.

Concurrently with movement of carriage 36 20 towards the path of the form block of the wrapping machine to effect transfer of a box structure by arm 35 from the aligning station, the members 74, 74 are therefore moved from the position shown in Fig. 7 toward the box-receiving position 25 shown in Fig. 9, the relative movement of the two transfer devices causing the box structure to be transported from the position shown in Fig. 8 transversely of the conveyor to the position shown in Fig. 9 at which it is received by 30 the box-holding members 77, 77. The distance between the center lines of the conveyor and of the form block is fixed for all sizes of boxes within the range of the machine; the strokes of the two transfer devices are therefore fixed and each 35 follows the law of harmonic motion insuring smooth operating action.

Preferably before the box structure is moved from the position shown in Fig. 9 to the position shown in Fig. 10, the suction applied through 40 the suction plate 37 to the box structure is cut off and substantially concurrently the suction is applied or increased through the ports 78 of the box-engaging members 77, 77. The valve mechanism for shifting the application of suction from 45 one of the transfer devices to the other is shown in Figs. 5 and 6.

The piston 88 of the suction valve V is connected by link 89 to the arm 90 rockable by the cam 91 on shaft 2 of the box machine. As the 50 pusher-arm 35 and the carriage members 74, 74 are moving toward each other, the valve piston 88 is in the position shown in Fig. 6, providing a path for suction through the plate 37, flexible hose 92, pipe 93, port 94 of valve V, about the piston 88, and thence through port 95 and pipe 96 to the intake of a suction pump not shown. The port 97 of the valve is blocked by the piston 88, preventing application of suction through the ports 78 and 81a of the box-engaging members 55 77, 77 and 81, 81 respectively of the transfer carriage.

Substantially concurrently with the raising of arm 35 to the position shown in Fig. 2, the piston valve is moved from the position shown in Fig. 6 65 to the position shown in Fig. 5 to close the port 94 and so discontinue application of suction through the plate 37 and substantially concurrently to permit application of suction through the port 97 which is in communication with the 70 suction ports 78 and 81a of the carriage members 74, 74. Suction may be continuously exerted through the ports 78 until the arm 35 moves from the position shown in Fig. 7 to the position shown in Fig. 8, at which time suction is transferred to 75

the suction plate 37 to hold the box blank to the member 35 for its movement toward the form block or, more specifically, at the box-receiving position of the carriage members 74, 74.

5 Preferably the transfer devices, the conveyor C, and the form block of the wrapping machine are so timed that the parts are in the position shown in Fig. 10 at or just before the end of the cycle of the machine. As there indicated, the 10 finished box has been, or is being ejected by the ejector 98, the conveyor C is stationary, the carriage members 74, 74 are in their box-receiving position, the pusher member 35 has completed its transfer movement of a box structure, and 15 member 35 and the aligning member 33a are in their raised positions.

When the operator presses the pedal 5, the two transfer devices move away from one another, the carriage members 74, 74 moving assembly A to the position shown in Fig. 7, in the path of the descending form block F, and the other transfer device comprising arm 35 returning to its position above the aligning station, Fig. 7. While the two transfer devices remain stationary at these positions, the form block in its descent carries the assembly from the position shown in Fig. 7 downwardly adjacent the various sheet-applying tools, and during this dwell of the transfer device the conveyor C operates to bring another box structure or assembly against the stop 29. The carriage is free to move to its box-receiving position as soon as the descending form block has removed the assembly therefrom. For holding the box ends against the form block until operation of the corner-lap tools, which apply the flaps f of the wrapper to the box ends, there may be utilized the holders 100 of the type described in Lange application Serial #86,591, filed June 22, 1936, or in lieu 30 thereof, the form block F may be of the suction type disclosed in Rider application Serial #86,221, filed June 20, 1936.

While the conveyor C is stationary, the member 33a of mechanism R swings from the position shown in Fig. 7 to the position shown in Fig. 8 to align a box structure or assembly with the form block, and the member 35 swings downwardly into engagement with the registered box structure, the valve V causing suction to be applied to the box structure through the plate 37 on arm 35. Substantially concurrently with interruption of movement of the conveyor, the two transfer devices move toward each other, the arm 35 moving the box assembly to the position shown in Fig. 9, and the carriage members 74 concurrently moving to the position shown in Fig. 9 to receive the box. During this movement of the transfer devices, and while they are still in the position shown in Fig. 9, the form block F may substantially complete its upward movement, the completed box having been removed therefrom by the stripper rods 99. While the transfer devices are in their respective positions shown in Fig. 9, the conveyor belt may begin its 60 movement to transport the next assembly toward the registering station. Before the end of the cycle of the machine, the pusher-arm 35 and the aligning arm 32 may be swung upwardly to the position shown in Fig. 10 to avoid obstruction to the next assembly to be or being transported to the registering station.

In the system as specifically described, the machine operator in each cycle of the machine, merely has to register a stayed or unstayed box 75 on a wrapper or group of detached tabs; all of

the other operations, including that of placing the box and wrapper assembly on the form block, are performed automatically. With some sacrifice of output, but yet with considerable improvement in this respect as compared with prior practice, the aligning mechanism R and transfer mechanism P and all their operating linkages and supports may be omitted. In this modification, Fig. 11, the operator sits more or less directly in front of the box machine M, and at that position registers boxes upon the wrappers or groups of tabs transported by conveyor C. Preferably, as shown in Fig. 2, the upper lift of the conveyor at the registering station is supported by a board or plate 101 to maintain the belt flat and serve as a registry table. In addition to forming assemblies, the operator, with this simplified construction, must push the assemblies between the spaced arms 74 of the transfer carriage. The consequent need for the operator to time her movements to that of the carriage to some extent reduces the proportion of the cycle during which the operator is free to perform the manual registering operation. However, since the carriage does not obstruct the movements of the operator and permits her to register a box on a wrapper whenever the conveyor is stationary, the box machine may be run at high speed and yet afford ample time in each cycle for the operator to register a box on a wrapper and push the assembly into the carriage. Furthermore, since the box-receiving position of the carriage is near the form-block side of the conveyor, the assembly may be moved from the conveyor almost as soon as the carriage begins its transfer movement, leaving the conveyor clear at the transfer station, thus making it feasible to start the conveyor before the transfer member completes its movement to the discharge position and, in any event, to effect movement of the conveyor within a period beginning shortly after the carriage has begun its movement from its assembly-receiving position and terminating before completion of the reverse movement of the carriage to its assembly-receiving position.

When both transfer devices are used, the registration of a box upon a wrapper or tabs may be performed at any time in the cycle except while the conveyor C is in motion. Since in the particular arrangement described, the conveyor is moving for approximately 160 degrees of the machine cycle, the machine may be run continuously at speeds in excess of 30 cycles per minute and yet provide ample time in each cycle for the operator to reach for a box structure and register it on the wrapper or group of tabs delivered in front of her by the conveyor C.

When the aligning device R and the transfer device P are omitted, there is then available approximately 100 degrees of the wrapping-machine cycle during which the registering operation may be effected. Cam 66 provides for suitable dwell of the carriage T at its box-receiving and box-discharge positions and rapid movement of the carriage toward box-receiving position shortly after the descending form block removes a box structure therefrom. A box or assembly can be pushed into the carriage as it approaches or moves from its box-receiving position, as well as during its dwell at box-receiving position.

Conversion to a full automatic system in which none of the operations are performed manually may be effected, as above described, by utilization of the blank-bending and transfer mechanism disclosed in Stokes U. S. Patent #2,018,237. 75

While I have illustrated and described a preferred arrangement, it is to be understood my invention is not limited thereto, but is coextensive in scope with the appended claims.

5. What I claim is:

1. A box machine comprising reciprocating form-block structure, and means for transferring box structure into the path of said form-block structure comprising transfer structures movable toward and from each other during the cycle of said machine, one of said transfer structures, during the movement of said transfer structures toward each other, moving the box structure toward the path of said form-block structure, and the other of said transfer structures, during the movement of said transfer structures away from one another, transporting the box structure into the path of said form-block structure.

2. A box machine comprising reciprocating form-block structure, and means for transferring box structure into the path of said form-block structure comprising transfer structures movable toward and from each other during the cycle of the machine, one of said transfer structures, during the movement toward each other of said transfer structures, pushing the box structure toward the path of said form-block structure, and the other of said transfer structures, during the movement of said transfer structures away from one another, pulling the box structure into the path of said form-block structure.

3. A box machine comprising reciprocating form-block structure, an alignment station, a transfer member movable to move an assembly comprising box structure and partially applied sheet material from said station toward the path of said form-block structure, a transfer member movable to receive an assembly from said first transfer member and transport it into the path of said form-block structure, and mechanism operating in timed relation to said form-block structure for moving said transfer members toward and from each other.

4. A box machine comprising form-block structure reciprocating to and from a position at which it receives an assembly comprising box structure and partially applied sheet material, sheet-applying tools adjacent the path of said form-block structure, and transfer structures movable toward each other during movement of said form-block structure from said box-receiving position toward said sheet-applying tools and movable away from each other during movement of said form-block structure toward said box-receiving position, one of said transfer structures moving an assembly toward the path of said form-block structure during the movement toward each other of said transfer structures, and the other of said transfer structures during the movement from each other of said transfer structures moving the assembly into said path of the form-block structure.

5. A box-machine comprising form-block structure, an alignment station, a transfer structure movable in one direction to feed an assembly comprising box structure and partially applied sheet material from said station toward said form-block structure and movable in reverse direction in a different path to permit movement of another assembly to said station, and a second transfer structure movable toward said station to receive an assembly from said first transfer structure and movable in reverse direction to transport the received assembly to said form-block structure.

75. 6. A box machine comprising form-block struc-

ture for receiving an assembly comprising box structure and partially applied sheet material, an alignment station, transfer structures, and mechanism operating to move said transfer structures toward each other for transfer by one of said transfer structures of an assembly from said station to the other of said transfer structures and subsequently to move said transfer structures away from each other for transfer by the other of said transfer structures of the received assembly to said form-block and for return of said one of said transfer structures toward said station.

7. A box machine comprising reciprocating form-block structure, an alignment station to one side of the path of said form-block structure, supporting structure on the other side of said path, spaced box-engaging members extending from said supporting structure toward said station, and mechanism for moving said supporting structure toward said path for positioning said members to receive a box structure and for moving said supporting structure away from said path to transport the received box structure into said path.

8. A box machine comprising reciprocating form-block structure, sheet-applying tools adjacent the path of said form-block structure, a pair of spaced members for engaging and holding erected walls of a box structure disposed to one side of the path of said form-block structure, supporting structure for said members disposed on the opposite side of said path, and mechanism operable after said form-block structure has passed its box-receiving position in moving toward said tools to move said supporting structure toward said path for reception of box structure by said spaced members and operable after said form-block structure has passed its box-receiving position in reverse direction to move said supporting structure away from said path to effect transport of the received box structure into said path.

9. A box machine comprising reciprocating form-block structure, sheet-applying tools adjacent the path of said form-block structure, means for transferring box structure into the path of said form-block structure comprising supporting structure movable toward and from the path of said form block, a pair of members each attached at one end to said supporting structure and spaced to straddle the form block when in box-receiving position, box-holding means carried by the free ends of said members, and mechanism operable after said form-block structure has moved from said box-receiving position toward said sheet-applying tools to move said supporting structure toward the path of said form-block structure for reception of box structure by said box-holding means of said spaced members and operable after said form-block structure has passed said box-receiving position in reverse direction to move said supporting structure away from said path to effect transport of the received box structure into the path of said form-block structure.

10. A box machine comprising reciprocating form-block structure, a pair of spaced members having suction ports for engaging the exterior faces of erected opposite walls of a box structure, and mechanism for moving said members in one direction to receive a box structure and in reverse direction to pull the received box structure into the path of said form-block structure.

11. A box machine comprising reciprocating

form-block structure, a pair of spaced members having suction ports for engaging the exterior faces of erected walls of a box structure, mechanism for moving said members in forward direction to receive a box structure and in reverse direction to draw the received box structure into the path of said form-block structure, and means for effecting application of suction through said ports during movement of said members in said 10 reverse direction.

12. A box machine comprising reciprocating form-block structure, a pair of spaced members having suction ports for engaging the exterior faces of erected walls of a box structure, a conveyor, mechanism for moving said members in forward direction toward said conveyor to receive a box structure pushed across the conveyor between said members and for moving said members in reverse direction to draw the received box 15 structure into the path of said form-block structure, and means for interrupting application of suction through said ports during movement of said members in forward direction.

13. A box machine comprising form-block structure, a pair of spaced members for engaging and holding erected walls of a box structure, mechanism for moving said members in one direction to receive a box structure and in reverse direction to transport the received box structure 20 to said form-block structure, and structure reciprocating toward and from said form-block structure for feeding a box structure into engagement with said spaced members for transport thereby.

14. A box machine comprising form-block structure, a pair of spaced members having suction ports for engaging erected walls of a box structure, mechanism for moving said members in one direction to receive the box structure and in 25 reverse direction to transport the received box structure, reciprocable suction means for feeding a box structure into engagement with said spaced members, and means for interrupting application of suction through said ports during movement of said members toward said reciprocable means and for interrupting application of suction by said reciprocable means during movement of said members in said reverse direction.

15. A box machine comprising reciprocating form-block structure, support members disposed on opposite sides of the path of said form-block structure, mechanism for moving said members toward and from one another, suction devices carried by said support members for successively holding box structure thereto, and means for supplying suction to said devices alternately, as each moves toward said form-block structure.

16. A box machine comprising form-block structure, an alignment station, a supporting structure, mechanism for moving said structure toward and away from said form-block structure, a box-engaging member pivotally mounted on said supporting structure, and mechanism for swinging said member in engagement with box structure at said station for movement of said supporting structure toward said form-block structure and for swinging said member in reverse direction for reverse movement of said supporting structure.

17. A box machine comprising form-block structure, an alignment station, a supporting structure, mechanism for moving said structure toward and away from said form-block structure, a suction member pivotally mounted on said supporting structure, mechanism for swinging said

member into engagement with box structure at said station for movement of said supporting structure toward said form-block structure and for swinging said member in reverse direction for reverse movement of said supporting structure, and means for applying suction through said member for forward movement of said supporting structure and for reducing the suction for reverse movement of said supporting structure. 5

18. A box machine comprising form-block structure, an alignment station, transfer structure movable toward said form-block for moving box structure from said station, and mechanism operable to align the box structure at said station with the form-block structure prior to movement of the box structure from the station by said transfer structure. 10

19. A box machine comprising form-block structure, an alignment station, transfer structure movable toward said form-block structure for moving box structure from said station and movable in reverse direction in a different path to permit movement of a second box structure to said station, and mechanism operable before the next movement of said transfer structure toward said form-block structure to align said second box structure. 15

20. A box machine comprising form-block structure, a conveyor for box structures disposed on one side of said form-block structure, supporting structure on the opposite side of said form-block structure, spaced box-transfer members extending from said supporting structure toward said conveyor, mechanism for moving said supporting structure toward said form-block structure for positioning said members to receive a box structure on said conveyor, and means operable to align the box structure on said conveyor prior to its movement by said transfer members. 25

21. A box machine comprising reciprocating form-block structure, a conveyor for box structures disposed on one side of said form-block structure, supporting structure on the opposite side of said form-block structure, spaced box-transfer members extending from said supporting structure toward said conveyor, and mechanism for moving said supporting structure toward said form-block structure to position said members to receive a box structure from said conveyor and for moving said supporting structure away from said form-block structure to move the received box structure into the path of said form-block structure. 40

22. A box machine comprising form-block structure, an intermittently operated conveyor for transporting box structures adjacent said form-block structure, and means for transferring the box structures in succession from said conveyor to said form-block structure comprising transfer structures movable toward and from each other while said conveyor is at rest, one of said transfer structures during movement of the transfer structures toward each other moving a box structure along the conveyor for reception by the other transfer structure, and the other of said transfer structures, during the movement of said transfer structures away from each other, transferring the received box structure from said conveyor into the path of said form-block structure. 55

23. A box machine comprising form-block structure, a conveyor for transporting box structures, a transfer member movable toward and away from said conveyor and toward and away from said form-block structure, and mechanism operable 60

5 to move said transfer member toward said conveyor and said form-block structure to move a box structure along the conveyor toward said form-block structure and subsequently to move said transfer member away from said conveyor and said form-block structure.

10 24. A box machine comprising form-block structure, a conveyor for transporting box structures, a transfer member movable toward and away from said conveyor and toward and away from said form-block structure, mechanism operable while said conveyor is at rest to move said transfer member toward said conveyor and said form-block structure to move a box structure 15 along the conveyor toward said form-block structure and subsequently to move said transfer member away from said conveyor and said form-block structure, and mechanism for effecting operation of said conveyor while said transfer member is 20 away from said conveyor.

25 25. A box machine comprising form-block structure, a conveyor for transporting box structures, an aligning member movable to engage the box structures in succession on said conveyor, a transfer member movable toward and away from said conveyor and toward and away from said form-block structure, mechanism operable to move said transfer member toward said conveyor and toward said form-block structure to move 30 an aligned box structure toward said form-block structure and subsequently to move said transfer member away from said conveyor and said form-block structure, and mechanism for operating said aligning member while said transfer member 35 is away from said conveyor.

40 26. A box machine comprising form-block structure, a conveyor for transporting box structures, an aligning member movable to engage the box structures in succession on said conveyor, a transfer member movable toward and away from said conveyor and toward and away from said form-block structure, mechanism operable while said conveyor is at rest to move said transfer member toward said conveyor and said form-block structure to move an aligned box structure toward said form-block structure, means effecting 45 operation of said conveyor while said transfer member is away from said conveyor, and mechanism for operating said aligning member after operation of said conveyor and while said transfer member is away from said conveyor.

55 27. A box machine comprising form-block structure, a conveyor for box structures, a carriage reciprocable from a box-receiving position above said conveyor and between the path of said form-block structure and the line of travel of said box structures with said conveyor to a position for holding box structure in the path of said form-block structure, box-holding means movable 60 with said carriage for engagement, at said box-receiving position, with box structure at the side thereof nearest said form-block path, mechanism for moving said carriage to its box-receiving position while said conveyor is at rest, and mechanism for operating said conveyor to bring a box structure adjacent the box-receiving position of said carriage while the carriage is away therefrom.

65 28. A box machine comprising form-block structure, an intermittently operated conveyor for transporting box structures, a carriage reciprocable from a receiving position above said conveyor to a discharging position in the path of said form-block structure, mechanism for moving said carriage from its receiving position while said conveyor is at rest, and a transfer member for

engaging a box structure on said conveyor and moving it, while said conveyor is at rest, to said carriage while in receiving position.

70 29. A box machine comprising form-block structure, a conveyor for box structures, a carriage reciprocable from a box-receiving position above said conveyor to a discharge position in the path of said form-block structure, a box-engaging member movable toward and from said conveyor and toward and from said box-receiving 10 position, mechanism operable while said conveyor is at rest to move said carriage and said member toward said box-receiving position, and mechanism for operating said conveyor while said carriage is away from said box-receiving position 15 and said member is away from said conveyor.

20 30. A box machine comprising form-block structure, a conveyor for box structures, a carriage reciprocable from a box-receiving position above said conveyor to a discharge position in the 20 path of said form-block structure, a box-engaging member movable toward and from said conveyor and toward and from said box-receiving position, mechanism operable while said conveyor is at rest to move said carriage and said 25 member toward said box-receiving position, mechanism for operating said conveyor while said carriage is in said discharge position and said member is away from said conveyor, structure for aligning a box structure for transfer by 30 said member, and mechanism for effecting operation of said aligning structure after operation of said conveyor and while said member is away from said box-receiving position.

35 31. A box machine comprising form-block structure, an assembly station at which box structures are adhesively attached to sheet material, a conveyor for transporting the assemblies from said station, a carriage reciprocable from an assembly-receiving position above said conveyor to 40 a discharge position in the path of said form-block structure, an assembly-engaging member movable toward and from said conveyor and toward and away from said assembly-receiving position, mechanism operable while said conveyor is 45 at rest to move said carriage and said member toward said assembly-receiving position, and mechanism for operating said conveyor while said carriage is away from said box-receiving position and while said member is away from said 50 conveyor.

55 32. A box machine comprising form-block structure, an intermittently operated conveyor for transporting box structure, stop structure in alignment with said form-block structure for engaging one wall of a box structure on said conveyor, an aligning member movable to engage the opposite wall of said box structure and align it with said form-block structure, a carriage for transporting an aligned box structure from said conveyor into the path of said form-block structure, means for pushing an aligned box structure into said carriage, and means effecting operation of said conveyor when said carriage, said movable aligning member and said pushing member 60 are out of the path of box structures on the conveyor.

65 33. A box machine comprising form-block structure, and means for transporting unstayed boxes into the path of said form-block structure 70 comprising a pair of spaced members for engaging opposite erected walls of an unstayed box and extending beneath the leading unerected wall.

75 34. A box machine comprising form-block structure, a conveyor extending adjacent the path

of said form-block structure, a carriage movable from an assembly-receiving position above the conveyor into the path of said form-block structure, box-holding means movable with said carriage for engagement, at said assembly-receiving position, with an assembly at the side thereof nearest said form-block path, and means for operating said conveyor step by step timed to complete a step of said conveyor before said carriage completes its movement to said assembly-receiving position.

35. A box machine comprising form-block structure, a conveyor extending adjacent the path of said form-block structure, a carriage for transporting box-structure from said conveyor into the path of said form-block structure, and mechanism for reciprocating said carriage from the box-receiving position of said carriage intermediate the center line of said conveyor and said path to and from the box-discharge position of said carriage in said path.

36. A box machine comprising form-block structure, a conveyor extending adjacent the path of said form-block structure, a carriage movable from an assembly-receiving position intermediate the center line of said conveyor and said path to an assembly-discharge position in said path, mechanism for effecting reciprocation of said carriage, and means for intermittently operating said conveyor timed to effect its movement while said carriage is away from its assembly-receiving position.

37. A box machine comprising form-block structure, a conveyor extending adjacent the path of said form-block structure, a carriage movable from a box-receiving position intermediate the center line of said conveyor and said path to an assembly-discharge station in said path, suction grippers on said carriage for engaging walls of box structure for transport by said carriage, mechanism for effecting reciprocation of said carriage between said receiving and discharge positions, and mechanism for operating said conveyor step by step timed to complete a step of its movement while said carriage is away from said box-receiving position.

38. A box machine comprising form-block structure, a conveyor for transporting assemblies, comprising box structures registered on sheet material, to a position thereon adjacent said box machine, mechanism operable to displace the assemblies in succession from said position toward the edge of the conveyor nearest the path of said form-block structure, and mechanism operable to receive the displaced assemblies and transport them in succession into said path of the form-block structure.

39. A box machine comprising form-block structure, and means for feeding assemblies comprising box structures registered on sheet assemblies into the path of said form-block structure comprising a conveyor, feeding devices reciprocating transversely of said conveyor toward and from each other and toward and away from the path of said form-block structure, said conveyor transporting the assemblies to one of said feeding devices, said one of said feeding devices transporting the assemblies in succession transversely of the conveyor to the other feeding device, and said last-named feeding device transferring the assemblies in succession into the path of said form-block structure.

40. A box machine comprising reciprocating form-block structure, and means for pulling box structures into the path of said form-block struc-

ture comprising members reciprocating in unison on opposite sides of the path of said form-block structure and having their free ends extending forwardly toward an operator who disposes a box structure therebetween.

41. A box machine comprising reciprocating form-block structure, and means for pulling box structures into the path of said form-block structure comprising members reciprocating in unison on opposite sides of the path of said form-block structure with their forward ends presented toward an operator and free of any interconnecting structure, and suction grippers at the forward ends of said members to hold thereto a box structure disposed therebetween by the operator.

42. A box machine comprising reciprocating form-block structure, and means for pulling box structures into the path of said form-block structure comprising members reciprocating in unison on opposite sides of the path of said form-block structure and free of any interconnecting structure which crosses said path or which obstructs the space between the forward ends of said members and said path, stops at the forward ends of said members, and means at the forward ends of said members to hold thereto a box disposed therebetween by an operator in position determined by said stops.

43. A machine comprising a reciprocating form-block structure, an intermittently operated conveyor extending adjacent the path of said structure, and means for pulling box structure into said path comprising members reciprocating in unison on opposite sides of the form-block structure and whose free ends extend over said conveyor to receive box structure pushed along the conveyor while it is at rest.

44. A box machine comprising reciprocating form-block structure, and means for pulling box structures from a transfer station into the path of said form-block structure comprising a reciprocable carriage having transfer members which straddle the path of movement of said form-block structure and whose free ends are presented toward said transfer station.

45. A box machine comprising reciprocating form-block structure, reciprocating structure for moving an assembly comprising box structure and partially applied sheet material into the path of said form-block structure, and pneumatic means for supporting the leading unapplied panel of said sheet material during said movement of the assembly by said reciprocating structure.

46. A box machine comprising reciprocatory form-block structure, means for pulling an assembly comprising box structure and partially applied sheet material from a transfer station into the path of said form-block structure comprising members reciprocating in unison on opposite sides of the path of movement of said form-block structure and whose free ends, presented toward said transfer station, receive the box structure, and pneumatic means for supporting the leading unapplied panel of said sheet material during the movement of the assembly into said path.

47. A box machine comprising reciprocating form-block structure for receiving at a station intermediate the limits of its path of movement an assembly comprising box structure and sheet material partially applied thereto, sheet-applying tools adjacent said path beyond said station, assembly transfer means comprising members between which said form-block structure reciprocates, and mechanism operable after said form-

block structure has passed said station for movement adjacent said tools to move said members to present their leading ends to an assembly to be transferred and operable after said form-block structure has passed said station in the reverse direction to move said members in reverse direction to pull the assembly into said station.

48. A box machine comprising form-block structure, a conveyor for transporting box structures to a transfer station adjacent the path of movement of said form-block structure, means for transporting box structures from said transfer station into said path comprising a member reciprocable toward and away from said path, and means for moving said member toward said conveyor to engage a box structure for movement therewith toward said path and for moving said member away from said conveyor during its movement away from said path in avoidance of obstruction to movement of the next box structure by said conveyor to said transfer station.

49. A box machine comprising reciprocating form-block structure, a transfer member movable successively to move assemblies each comprising box structure and a partially applied tabbed wrapper toward the path of said form-block structure, a second transfer member adapted individually to receive the successive assemblies and transport them in succession into the path of said form-block structure, and mechanism operating in timed relation to said form-block structure for moving said members toward and from each other.

50. A box machine comprising reciprocating form-block structure, reciprocating transfer structures movable toward and from each other during the cycle of said machine, one of said transfer structures during its movement toward the other transporting and delivering thereto an assembly comprising box structure and a partially-applied tabbed wrapper, and the other of said transfer structures by its movement from said one of said transfer structures delivering the assembly into the path of said form-block structure.

51. A box machine comprising form-block structure reciprocating through a station at which it receives an assembly comprising box-structure and partially applied sheet material, sheet-applying tools adjacent the path of said form-block structure on one side of said station, a conveyor for transporting assemblies, transfer structures movable toward and from each other above said conveyor, and mechanism operating in timed relation to said form-block structure for moving said transfer structures toward each other while said form-block structure is on said one side of said station, one of said structures during said movement transporting an assembly with respect to said conveyor and delivering it to the other of said transfer structures, and for moving said transfer structures away from each other while said form-block structure is on the

other side of said station to effect delivery of the assembly by said other of said transfer structures to said station.

52. A box machine comprising form-block structure reciprocating through a station at which it receives an assembly comprising box structure and partially applied sheet material, an alignment station to one side of said assembly-receiving station, movable supporting structure on the other side of said assembly-receiving station, assembly-engaging structure extending from said supporting structure toward said alignment station, and mechanism for reciprocating said supporting structure in timed relation to said form-block structure for moving said assembly-engaging structure to pull assemblies in succession from said alignment station to said assembly-receiving station.

53. A box machine comprising form-block structure reciprocating through a station at which it receives an assembly comprising box structure and partially applied sheet material, assembly transfer means comprising reciprocating structure through which suction is exerted upon an exterior face of the assembly to hold it thereto, and mechanism for moving said last-named structure in one direction to pull an assembly to said station and in reverse direction to engage the next assembly to be pulled thereby to said station.

54. A box machine comprising form-block structure reciprocating through a station at which it receives an assembly comprising box structure and sheet material partially applied thereto, means for transporting assemblies to said station comprising a conveyor, a transfer structure for displacing the assemblies in succession while on said conveyor, and a second transfer structure for receiving the displaced assemblies delivered thereto by said first transfer structure and transporting them to said station, and mechanism for aligning the assemblies in succession prior to their displacement by said first transfer structure.

55. In a system comprising mechanism for feeding, coating with adhesive, and applying tabs to wrappers, and a box machine having form-block structure reciprocating through a receiving station at which it receives an assembly comprising box structure and a tabbed wrapper partially applied thereto, a conveyor for transporting the tabbed wrappers from said mechanism through a station in which box structures are registered on the tabbed wrappers to form assemblies, means for aligning the assemblies on said conveyor with said receiving station, and transfer structures movable toward each other to effect by one of said transfer structures transfer of an aligned assembly to the other of said transfer structures and movable away from each other to effect delivery of an assembly to said receiving station by said other of said transfer structures.

LUDWIG H. LANGE.
